(57) **CLAIM**

The ornamental design for an LED light, as shown and described.

DESCRIPTION

FIG. 1 is a front perspective view of a lampshade of an LED light, shown separately for illustration;
FIG. 2 is rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 shown in FIG. 1;
FIG. 10 is an enlarged view of portion 10 shown in FIG. 1;
FIG. 11 is an enlarged view of portion 11 shown in FIG. 2;
FIG. 12 is an enlarged view of portion 12 shown in FIG. 2;
FIG. 13 is perspective view of a light body of an LED light, shown separately for illustration;
FIG. 14 is another perspective view thereof;
FIG. 15 is a front elevational view thereof;
FIG. 16 is a rear elevational view thereof;
FIG. 17 is a left side elevational view thereof;
FIG. 18 is a right side elevational view thereof;
FIG. 19 is a top plan view thereof;
FIG. 20 is a bottom plan view thereof;
FIG. 21 is an enlarged view of portion 21 shown in FIG. 13;
FIG. 22 is an enlarged view of portion 22 shown in FIG. 16;
FIG. 23 is a perspective view of the LED light;
FIG. 24 is an enlarged view of portion 24 shown in FIG. 23;
FIG. 25 is an enlarged view of portion 25 shown in FIG. 23;
FIG. 26 is an enlarged view of portion 26 shown in FIG. 23;
FIG. 27 is a perspective view of the LED light where the LED light is in a first configuration of use;
FIG. 28 is a perspective view of the LED light where the LED light is in a second configuration of use;
FIG. 29 is a perspective view of the LED light where the LED light is in a third configuration of use; and,
FIG. 30 is a perspective view of the LED light where the LED light is in a fourth configuration of use.

The broken lines shown in the drawings are included for the purpose of illustrating portions and environmental elements of the LED light, and form no part of the claimed design.
